UNITED STATES PATENT OFFICE

HOBART S. GEER, OF CORONA, NEW YORK, ASSIGNOR TO AMERICAN SAFETY DEVICE CO., OF NEW YORK, N. Y., A CORPORATION OF NEW YORK

HOISTING DEVICE

Application filed September 26, 1930. Serial No. 484,507.

- This invention relates to hoisting devices, and more particularly to scaffold hoists such as are generally used for raising and lowering scaffolds in the course of erection of a building. 5
- It is the primary object and purpose of the present invention to provide such a hoisting device which is provided with reliable and positively operating safety guard means 10 which will effectively prevent the descent of the scaffold, and possible serious accident resulting in injury or death, in the event that the workmen should lose control of the hoisting device during operation thereof.
- 15 It is one of the important features of my present improvements to provide worm gearing for the operation of the rope or cable drum during unwinding of the cable therefrom for the lowering of the scaffold and 20 means connected with the operating handle for the worm gearing and normally locking said gearing and the drum against such rotation, while permitting of the rotation of the drum in the opposite direction to wind the 25 rope or cable thereon.
- It is a further object of the invention to provide upon one end of the drum spring 30 pressed pivoted pawls cooperating with a ratchet connected with the worm gear where- 35 by said drum and gear will rotate as a unit in an anti-clockwise direction to lower the scaffold, and holding devices detachably engageable with said pawls to hold the same out of contact with the ratchet to permit of free rotation of the drum in the unreeling of the cable therefrom preparatory to rigging.
- It is also another object of the invention to 40 provide an operating lever for rotating the drum in a clockwise direction to wind the cable thereon having a pawl cooperating with a ratchet on the other end of the drum and means for releasably locking said pawl upon the lever in a disengaged position for unreeling the cable from the drum. There is also 45 provided an additional safety pawl mounted on the machine frame and cooperating with said ratchet.
- It is a further general object of the invention to provide a hoisting device of this character having the above noted improvements,
- which is relatively simple in its construction, light in weight and may be readily operated with a minimum of manual labor.
- With the above and other objects in view, the invention consists in the improved hoisting device, and in the form, construction and relative arrangement of the several parts as will be hereinafter more fully described, illustrated in the accompanying drawings, and subsequently incorporated in the subjoined 55 claims.
- In the drawings, wherein I have disclosed one simple and practical embodiment of my invention, and in which similar reference characters designate corresponding parts 60 throughout the several views,—
- Figure 1 is an end elevation of a hoisting machine embodying my present improvements; 65
- Fig. 2 is a side elevation thereof; 70
- Fig. 3 is a detail view showing the locking clutch for the worm gearing in its released position;
- Fig. 4 is an elevation similar to Fig. 1 of the opposite end of the machine; 75
- Fig. 5 is an enlarged vertical sectional view through the drum and worm gearing taken substantially on the line 5—5 of Fig. 6;
- Fig. 6 is a section taken on the line 6—6 80 of Fig. 5, and
- Fig. 7 is a detail perspective view of one of the pawl holding clips.
- Referring in detail to the drawings, 5 designates two spaced vertically disposed 85 end frame bars connected adjacent their upper and lower ends by the tie rods 6 and 7 respectively. Below the rod 7, the frame bars are divergently extended inwardly towards each other and have their extremities extended downwardly in parallel relation between which the upper ends of a scaffold supporting stirrup frame generally indicated at 8 are rigidly fixed. 90
- The drum 9 is rotatably supported between the frame bars 5 upon the shaft 10, one end or head of this drum being in the form of a ratchet 11. Between said ratchet and the adjacent frame bar 5, the end of a lever 12 is loosely mounted on the shaft 10 95
- 100

for vertical swinging movement. This lever carries a pawl 13 normally urged by the spring 14 into engagement with the teeth of the ratchet 11. The pawl 13 carries an angularly projecting arm 15 terminating in an apertured lug 16. The aperture 17 in this lug is adapted to be disposed in registering relation with a similar aperture 18 in the lever 12 when the pawl 13 is moved against the action of spring 14 out of contact with the teeth of the ratchet 11. These registering apertures are adapted to receive a movable pin 19 which may be conveniently attached to the lever 12 by means of a short length of chain 20. When unreeling the rope or cable indicated at R from the drum preparatory to rigging of the scaffold, the pawl 13 may thus be locked upon the lever in an inoperative position. The safety pawl shown at 21 which is held in engagement with the teeth of ratchet 11 by the spring 22, must of course, also be disengaged from said ratchet, as well as the pawls which are associated with the worm gearing to be hereinafter referred to. In order that the pawl 21 may be easily held in its released position, I form the same with an upwardly obliquely projecting hand piece shown at 23 which may be easily engaged by the fingers of the operator grasping the frame bar 5 and pressed inwardly towards said frame bar.

Above the pawl 21, a guide sheave 24 for the rope or cable R is suitably mounted upon the upper tie rod 6.

Between the opposite end or head 25 the drum 9 and the other vertical bar 5 of the frame, the worm gear 26 is loosely mounted on the shaft 10. A ratchet 27 may be integrally or otherwise connected with the gear 26 and is disposed closely adjacent to the drum head 25 upon which, at diametrically opposite sides of said ratchet, the pawls 28 are pivotally mounted to coact with the teeth of the ratchet and thereby connect the worm gear with the drum for rotation as a unit in an anti-clockwise direction to permit unreeling of the rope or cable R of the drum. The pawls 28 are held in engagement with the ratchet 27 by suitable leaf springs 29 attached at one of their ends to the flanged edges of the metal strips 30 secured to the face of the drum head 25.

Below the worm gear 26, a horizontally disposed U-shaped bracket member 31 is suitably fixed to the machine frame, and in the spaced arms of this bracket member, the opposite ends of the worm 32 are journalled, said worm being engaged with the lower side of the worm gear 26. The outer face of one of the arms of the bracket 31 is formed with a boss having clutch teeth 33 with which a sliding clutch member 34 on the extended end 35 of the worm shaft is normally held in engagement by means of the coil spring 36

surrounding said shaft between said clutch member and the end of an operating handle 37 pivoted to the end of the shaft 35 as at 38. One end of a link 39 is pivotally connected with the clutch member 34 and has its other end pivoted to the operating handle 37 below the pivot 38 as indicated at 40. Thus, it will be understood that normally the handle 37 is held in the angular relation with respect to the shaft 35 as seen in Fig. 1 of the drawings, while the clutch member 34 being engaged with the clutch teeth 33 of the fixed bracket thereby locks the worm 32 against rotation, preventing an anti-clockwise rotation of the gear 26 and the drum 9 and the unreeling of the rope or cable from the latter. When it is desired to unreel the cable, preparatory to rigging, the locking pawls 28 are held out of engagement with the ratchet teeth 27 by means of the metal clips 41 shown in Figs. 6 and 7 of the drawings. After the pawls are pressed away from the ratchet 26 against the action of springs 29, one of the angular ends of the clips are engaged against the inner edges of the pawls while the other angular ends of said clips are engaged over the flanges of the metal strips 30. Thus, after securing pawl 13 in its released position by means of the pin 19 on lever 12 and disengaging the safety pawl 21 from the ratchet 11, the rope or cable may be freely unwound from the drum.

Having above fully described the several mechanical parts of the hoisting machine, its operation will be understood as follows:

In rotating the drum in a clockwise direction with reference to Fig. 1 of the drawings to wind the cable thereon, the lever 12 is vertically manipulated, and in each down stroke of said lever, the pawl 13 engaging one of the teeth of the ratchet 11, rotates said drum to wind the cable thereon, the pawls 28 at the opposite end of the drum moving idly over the teeth of the worm gear 26, which together with the worm 32 are locked against rotation by the clutch means 33, 34. In the event of breakage of any of the parts at the latter end of the drum, failure to release the pawls 28, or the accidental disengagement of the clutch member 34 from the teeth 33, the descent of the scaffold would be limited by contact of the lever 12 in its upward swinging movement with the upper end of the machine frame, if the safety pawl 21 should also be broken or accidentally released. Thus, it will be seen that my present improvements provide three safety guards against accidental release of the drum and descent of the scaffold, first, the clutch lock 33, 34, second, the pawl 21, and thirdly, the operating lever 12 which by contact with the upper end of the frame, in the event of failure of both of the first named safety devices, will prevent the descent of the scaffold.

When the scaffold is to be lowered, the op-

erator first disengages the pawl 18 from the teeth of the ratchet 11 and locks the same to the lever 12 by the pin 19. While then holding one hand against the part 23 of pawl 21 to retain the latter in disengaged position with respect to ratchet 11, he grasps the crank arm of handle 37 and pulls the same laterally to the position seen in Fig. 3 of the drawings, thus moving clutch member 34 against the action of spring 36 out of engagement with the clutch teeth 33. The scaffold will then start to descend, the worm 32 being rotated through the connection of the locking pawls 28 on the drum and the ratchet 27 carried by worm gear 26. The operator of course, retains a firm grasp upon the crank handle 37, and controls the rapidity of descent of the scaffold. Should the operating handle 37 for any reason be released while lowering the scaffold, the spring 36 will immediately act to again engage clutch member 34 with the teeth 33, and thus check the further descent of the scaffold. Heretofore, contact of the worm operating handle with the end head of the drum has been relied upon to check the descent of the scaffold, but it has sometimes happened that either the handle or the end plate of the drum under the force of the impact would break or the handle end would be displaced to such an extent that it would pass outside of the drum head. Several serious accidents have been due to this failure. By means of my positive clutch lock for the worm gearing as above described, any possibility of the continued rotation of the worm shaft after the operating handle has been released, is precluded.

It will be apparent from the foregoing that the numerous safety features of my improved scaffolding hoists will be very effective in reducing the possibility of accidents resulting in death or injury to the workmen to a minimum. While the various parts are of rugged and durable construction, the machine as a whole is comparatively light in weight and may be easily handled in the rigging of the scaffold, and operated with comparatively little manual exertion. Also, it will be appreciated that my present improvements do not greatly complicate such devices as heretofore made and used, so that manufacturing costs thereof will not be materially increased.

While I have herein shown and described a simple and practical embodiment of the invention which has given very satisfactory results in actual use, it is nevertheless to be understood that the essential features thereof might also be embodied in various other alternative structural forms, and I accordingly reserve the privilege of resorting to all such legitimate changes therein as may be fairly embodied within the spirit and scope of the invention as claimed.

I claim:

1. In a hoisting machine, a frame, a cable drum revolubly mounted in the frame, means for operating the drum in one direction to wind the cable thereon, and means for controlling rotation of the drum in reverse direction to permit unreeling of the cable, said means including a loosely mounted gear, pawl and ratchet means connecting said gear with the drum for unitary rotation therewith in the latter direction, a drive gear in constant mesh with the first named gear, means connected with the drive gear to manually actuate the latter, and means for positively locking the drive gear against rotation including a part operatively connected to said actuating means and movable thereby to its released position.

2. In a hoisting machine, a frame, a cable drum revolubly mounted in the frame, means for operating the drum in one direction to wind the cable thereon, and means for controlling rotation of the drum in reverse direction to permit unreeling of the cable, said means including a loosely mounted gear, pawl and ratchet means connecting said gear with the drum for unitary rotation therewith in the latter direction, a drive gear in constant mesh with the first named gear, an operating handle for the drive gear pivotally connected therewith, and clutch means for positively locking said drive gear against rotation including a spring pressed clutch member and connecting means between the same and said operating handle whereby said clutch member is movable to a released position by an initial pivotal movement of said handle.

3. In a hoisting machine, a frame, a cable drum revolubly mounted in the frame, means for operating the drum in one direction to wind the cable thereon, and means for controlling rotation of the drum in reverse direction to permit unreeling of the cable, said means including a loosely mounted gear, pawl and ratchet means connecting said gear with the drum for unitary rotation therewith in the latter direction, a drive gear in constant mesh with the first named gear, an operating handle for the drive gear pivotally connected therewith, and clutch means for positively locking said drive gear against rotation including a spring pressed clutch member, and a link pivotally connected to said clutch member and to said operating handle whereby said clutch member is moved to a released position upon an initial pivotal movement of the handle.

4. In a hoisting machine, a frame, a cable drum revolubly mounted in the frame and having a ratchet head at one end thereof, a vertically swinging lever, a spring pressed pawl carried by the lever cooperating with the ratchet to rotate the drum in a direction to wind the cable thereon, means for releas-

ably locking said pawl upon the lever in an inoperative position, means mounted at the opposite end of the drum for rotating the same in a reverse direction to unreel the cable therefrom, said means including an operating handle, and means automatically effective upon the release of said handle to positively lock said last named means against rotation.

5. In a hoisting machine, a frame, a cable drum revolvably mounted in the frame and having a ratchet head at one end thereof, a vertically swinging lever, a spring pressed pawl carried by the lever cooperating with the ratchet to rotate the drum in a direction to wind the cable thereon, a member carried by said lever releasably engageable with a part of the pawl and with said lever to lock the pawl in an inoperative position, means mounted at the opposite end of the drum for rotating the same in a reverse direction to unreel the cable therefrom, said means including an operating handle, and means automatically effective upon the release of said handle to positively lock said last named means against rotation.

6. In a hoisting machine, a frame, a cable drum revolvably mounted in the frame and having a ratchet head at one end thereof, a vertically swinging lever, a spring pressed pawl carried by the lever cooperating with the ratchet to rotate the drum in a direction to wind the cable thereon, means for releasably locking said pawl upon the lever in an inoperative position, a safety pawl pivoted on the frame spring pressed into engagement with said ratchet head and having a hand piece obliquely projecting upwardly from its pivoted end for movement of said pawl to a disengaged position, means mounted at the opposite end of the drum for rotating the same in a reverse direction to unreel the cable therefrom, said means including an operating handle, and means automatically effective upon the release of said handle to positively lock said last named means against rotation.

7. In a scaffolding machine, a frame, a cable drum revolvably mounted therein, manually operable means for rotating the drum in one direction to wind the cable thereon, and means for rotating the drum in the opposite direction to permit unwinding of the cable, said means including a loosely mounted worm gear, a ratchet connected therewith, pawls pivotally mounted on one end of the drum and spring pressed into engagement with said ratchet, a worm engaged with said worm gear, a crank handle pivotally connected with the worm shaft, means normally locking said worm against rotation including a spring pressed clutch member, connecting means between the clutch member and the crank handle to move said clutch member to released position upon an initial pivotal movement of the crank handle, and members adapted to be detachably engaged with said

pawls and with parts fixed to the drum to hold said pawls out of engagement with the ratchet and permit of rotation of the drum to unreel the cable independently of said gearing.

In testimony that I claim the foregoing as my invention, I have signed my name hereto.

HOBART S. GEER.
